[57] CLAIM

The ornamental design for a combined radio and tape player, as shown and described.

DESCRIPTION

FIG. 1 is a top, front and right side perspective view of a combined radio and tape player showing my new design, with the tape compartment door in an open position;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.
